ASH TRAY

Isadore H. Dube, Cincinnati, Ohio

Application September 25, 1933, Serial No. 690,930

1 Claim. (Cl. 131—51)

The invention relates to a portable tray and more particularly to an ash tray for cigar and cigarette smoker's use.

The primary object of the invention is the provision of a tray of this character wherein lighted cigarettes when left in the tray will be prevented from falling therefrom and at the same time the burning ashes will break from the cigarette and be caught by the bowl of the tray, while the stub of such burning cigarette will have become shortened to fall within the said tray and thus eliminate the possibility of such stub leaving the said tray.

Another object of the invention is the provision of a tray of this character wherein its body is shaped to constitute a bowl having centrally thereof a raised portion formed with a fluted periphery presenting pockets or seats so that when a lighted cigar or cigarette is brought to rest within the bowl, the lighted end thereof will be accommodated in a seat or pocket so that such cigar or cigarette will be prevented from gravitation inwardly of the bowl beyond its position of rest and thus eliminating smoldering should the cigar or cigarette drop completely into such bowl and at the same time the cigar or cigarette at rest can be conveniently grasped or handled for the further smoking thereof on removal from the tray.

Another object of the invention is the provision of a tray of this character wherein the construction thereof is novel in form so as to properly hold a cigar or cigarette while lighted and at rest in the tray, and convenience to a smoker for access thereto when removing such cigar or cigarette when in the tray, to avoid the complete dropping of such cigar or cigarette thereinto.

A further object of the invention is the provision of a tray of this character which is extremely simple in construction, thoroughly reliable and efficient in its purposes, readily and easily portable, light in weight yet strong and durable, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claim hereunto appended.

In the accompanying drawing:

Figure 1 is a perspective view of a tray constructed in accordance with the invention and showing held thereby a lighted cigarette and a box of matches.

Figure 2 is a vertical sectional view through the tray.

Figure 3 is a perspective view of a slight modified form of tray showing a box of matches carried thereby and a cigarette at rest in the tray.

Similar reference characters indicate corresponding parts throughout the several views in the drawing.

Referring to the drawing in detail, particularly Figures 1 and 2, A designates generally an ash tray constructed in accordance with the invention and including a body 5 preferably made from glass, although it can be made from any other suitable material, and this body in its upper side is dished to form a bowl 6, in this instance of circular contour confronted with a marginal rim 7, while at one point peripherally of such body is an enlargement 8 having builded thereon a jaw 9, this being of a size and shape to permit of the fixing of a box of matches 11 for convenient access to the user of the tray and as is conventional.

Formed centrally of the bowl 6 is an enlargement constituting an abutment 12 circularly fluted or notched at the perimeter to provide the pockets or seats 13 so that on the placing of a cigar or cigarette on the tray A and within the bowl 6, its lighted end will occupy a seat or pocket 13 and this cigar or cigarette, the cigarette 14 being shown for illustrative purposes, will become at rest and be sustained at an angle for contact with the rim 7, whereby the gravitation or the dropping completely of such cigar or cigarette within the bowl is prevented. At the same time the cigar or cigarette is held for convenience to a smoker as such cigar or cigarette can be readily grasped for the removal of the same from the bowl and by sustaining the cigar or cigarette at rest, in a manner as before stated, there is no chance for undue smoldering at the lighted end thereof as is usual when the cigar or cigarette falls completely within the bowl.

In Figure 3 of the drawing there is shown a slight modification of the invention wherein the

bowl face 15 of the tray body 16 has formed therein the channels or grooves 17 merging with the pockets or seats 18 in the enlargement 19 at the center of such bowl and these grooves 17 5 constitute guideways for the cigar or cigarette when laid within the bowl, as should be apparent, to direct the lighted end of the cigar or cigarette into a seat or pocket 18. These grooves 17 open through the rim 20 of the body 16 and thus afford 10 seats 21 in said rim for a cigar or cigarette.

What is claimed is:

A tray of the kind described comprising a body formed in the shape of a bowl, and an enlargement within the bowl at the center thereof and having a notched perimeter, the enlargement being protruded perpendicularly from the bowl, and the outer wall of the body being of a height to incline a cigar or cigarette at rest thereon in the direction of the enlargement, the said bowl being formed with radially disposed grooves merging into said notches in the enlargement. 5
